UNITED STATES PATENT OFFICE

JAMES R. MOFFATT, OF CHICAGO, AND RALPH S. KELSO, OF ROCKFORD, ILLINOIS, AS-
SIGNORS TO UNION SPECIAL MACHINE COMPANY, OF CHICAGO, ILLINOIS, A COR-
PORATION OF ILLINOIS

TENSION-RELEASING MECHANISM FOR SEWING MACHINES

Original application filed June 4, 1926, Serial No. 113,714. Divided and this application filed August 9,
1928. Serial No. 298,514.

The invention relates to new and useful improvements in tension releasing mechanisms for sewing machines and more particularly to a tension releasing mechanism 5 for sewing machines having a series of stitching threads.

An object of the invention is to provide a machine having a series of stitching threads with tension discs for each thread, which are 10 mounted one above another, and in substantially the same vertical plane as the thread guides associated therewith, so that the threads pass in substantially the same plane from the guides receiving the thread 15 from the supply to the operating parts of the machine.

A further object of the invention is to provide a machine of the above type with means for lifting the presser foot and for simultaneously releasing all of the tensions wherein the tension releasing device for each pair of tension discs is below the disc with which it is associated.

A still further object of the invention is to 25 provide a tension releasing mechanism of the above type wherein the tension discs are mounted on supporting posts and held at a fixed distance from the supporting bracket for the posts so that the tension releasing 30 plate may slide freely on said posts between the tension discs and the supporting bracket.

These and other objects will in part be obvious and will in part be hereinafter more fully disclosed.

35 In the drawings which show by way of illustration one embodiment of the invention:—

Fig. 1 is a view showing in front elevation a sewing machine embodying the improvements.

Fig. 2 is a section on the line 2—2 of Fig. 1.

Fig. 3 is a plan view of the releasing plate showing a portion of the supporting bracket for the tensions.

40 Fig. 4 is a perspective view of the shifting

arm which releases and lifts the tension releasing plate.

Fig. 5 is a sectional view on the line 5—5 of Fig. 2.

Fig. 6 is a sectional view on the line 6—6 of 50 Fig. 1.

The invention is directed to an arrangement of the tensions for a sewing machine and the releasing mechanisms therefor. The sewing machine is provided with a plurality 55 of needle threads, a looper thread, and a cross thread, and there is a tension for each of these threads. The tension consists of two tension discs, one of which is spring pressed toward the other. These tension discs are mounted on posts and rest against a shoulder on the post. In the present embodiment of the invention, the posts are all arranged in a vertical plane and the tension discs are located one above another. The 60 threads are led through suitable guide eyes from the supply to these tension discs and thence to other guides and to the needles, looper, and cross thread laying mechanism. 65

Practically all of the thread guides for the 70 needle threads and the cross thread are located in the same plane as the tension discs. This enables the threads to run very freely as the turning of the thread about sharp angles has been avoided. Mounted on the 75 bracket supporting the posts carrying the tension discs is a plate which is preferably arranged to slide vertically on the posts. Said plate is common to all of the posts, and means is provided whereby when the presser foot is raised from the material, the plate is moved endwise in an upward direction. The plate carries an arm for each pair of tension discs and this arm has its upper edge wedge-shaped and the arm is so disposed that when 80 the plate is raised the wedge-shaped portion of the arm will pass between the tension discs and separate the same.

Referring more in detail to the drawings, 85 the invention is shown as applied to a sewing 90

machine having a standard 1 on which is mounted an overhanging arm 2. The machine is provided with a work supporting arm 3. The machine is shown more in detail in the parent application, Serial No. 113,714, filed June 4, 1926, of which the present application is a division. It is not thought necessary to describe in detail the work supporting arm or the parts contained thereon, or the means for actuating the same. Mounted in the overhanging arm is a needle bar 4 carrying three needles indicated at 5 in the drawings.

Associated with the needles is a cover thread laying mechanism including a thread guide 6 and a hook 7. There is a thread for each needle, a thread for the looper which cooperates with the three needles, and a thread for the cross thread laying mechanism. The needle threads are indicated at *n*, *n*, *n*. The cross thread is indicated at *c*, and the looper thread is indicated at *l*. These threads pass through guide eyes in a bar 8 attached to the standard of the machine. Mounted on the standard of the machine is a bracket 9. This bracket is secured to the standard by suitable screws and is provided with a vertical portion 10 between the points of attachment.

Attached to this vertical portion of the bracket is a support 11 for the tensions. This support extends in a vertical direction and is provided with side members 12 and 13, as shown in Fig. 5 of the drawings. The side member 12 is formed with a series of thread guides 14, one for each thread, and the member 13 is provided with a series of similar thread guides 15. Mounted on this support are five posts, each of which is indicated at 16. The post has a threaded connection to the support and each post has an integral collar 17 which is of greater diameter than the post. There are a pair of tension discs 18 and 19 on each post. A spring 20 on each post normally forces the tension disc 19 against the tension disc 18 and the tension discs against the shoulder formed by the collar at the base of the post.

A nut 21 is provided for varying the tension of the spring. These tension discs are all arranged one above another in a vertical line and in a vertical plane. The threads, after leaving the thread guides 14 pass through the tension discs, and thence through the thread guides 15. From this point the three needle threads are led to a thread guide 22 which is stationary, thence to a thread guide 23 carried by the needle bar and to the needles. The cross thread passes through a thread guide 24 and thence to the cross thread laying device. The looper thread passes down alongside the standard and into the arm and to the looper. As clearly shown in Fig. 1 of the drawings, the guides in the support for the threads are located a slight

distance beneath the tensions and the threads leaving the thread guides 14 pass in an upward direction over the post supporting the tension disc and thence in a downward direction to the thread guide 15. This insures that the thread shall remain between the tension discs when the grip of the tension discs is released therefrom.

Mounted for vertical movement on the support for the tension posts is a tension releasing plate 25. This tension releasing plate, as shown in Fig. 3, is provided with elongated slots 26. These slots engage over the posts and the collars at the base of the posts. The plate is of less thickness than the thickness of the collar, and, therefore, the plate is free to slide vertically on the posts in rear of the tension discs. Said plate is held to the support by screws 25a, 25a. This releasing plate 25 is provided with a series of arms 27, one arm for each pair of tension discs. The arms lie beneath the tension discs with which they are associated. The upper edge of each arm is beveled so as to form a wedge-shaped edge. When the plate 25 is raised the wedge-shaped edge of the arm will pass between the tension discs with which it is associated and separate the tension discs. Thus it is that the tension is released from the threads. When the plate 25 is lowered, then the arm is moved from between the tension discs and the tensions are restored to their normal grip on the threads. The tension releasing plate is also provided with an arm 28 which is bent at right angles to the plane of the plate and extends through a suitable opening 29 in the support 11. Mounted on the support 11 is a bracket which houses a spring 30. This spring bears on the arm 28 and normally presses the plate downward. The lower end of the opening 29 serves as a stop for limiting the downward movement of this tension releasing plate.

The presser bar is raised from the material by means of a lever 31. This lever may be connected through a suitable flexible means 32 with either a treadle or knee shift. The lever is attached to a shaft 33 which is provided with suitable means at the forward end of the machine for raising the presser foot. Mounted on this shaft 33 is an arm 34. The arm 34 is provided with a slot 35 through which a screw passes for securing said arm in different set positions to the lever 31. This arm projects laterally as indicated at 36 in Fig. 4 of the drawings, and the laterally projecting portion of the arm lies directly underneath the arm 28 which is attached to the tension releasing plate.

When the lever 31 is depressed this arm 36 will engage the arm 28 and lift the tension releasing plate which will cause the tension discs to be separated and the tension on all threads to be released. A spring 37 turns

the lever to a position where the arms are out of contact when the presser foot is lowered onto the material.

From the above it will be apparent that an arrangement of thread guides and tension discs have been provided wherein the threads are comparatively free from sharp turns so that they are free running during the operation of the machine. These tension discs are all arranged one above another and are released by a common plate moving in a vertical direction. Inasmuch as the arms on the tension releasing plate are beneath the tension discs gravity will aid in the moving of the arms away from the tension discs. Furthermore, by placing the tension posts in a horizontal position any dirt or lint accumulating between the tension discs will drop therefrom when said discs are separated. The tension releasing plate operates simultaneously on all the tension discs and this insures that all tensions will be released when the presser foot is raised. While all of the tensions are shown as disposed in a vertical plane one above the other, it will be obvious from certain aspects of the invention that some or all of the tensions may be otherwise disposed. The essential feature of this part of the invention consists in the arranging of a plurality of tensions in a vertical plane one above the other and providing a tension releasing plate common to the tension discs with means for simultaneously separating the tension discs when said plate is raised.

The guides 22 for the three needle threads are formed in a laterally extending portion of the arm 38. This arm 38 is adjustably secured in a sleeve 39 mounted on the end of an arm 40 which, in turn, is adjustably secured in a sleeve 41 carried by the bracket 42. The arm 40 is horizontal and capable of endwise adjustment. The arm 38 is also capable of vertical and oscillating adjustment in the sleeve at the end of the arm 40. Through these adjustments the thread guides 22 may be moved nearer to and farther from the thread guides 23 on the arm carried by the needle bar. By raising and lowering the arm 38 these thread guides may be set at a higher or lower point relative to the path of reciprocation of the thread guides 23 in the arm carried by the needle bar. Thus it is that the control on the needle threads may be varied through the shifting of these stationary thread guides 22.

It will be obvious that minor changes in the details of construction may be made without departing from the spirit of the invention as set forth in the appended claims.

Having fully described our invention, what we claim as new and desire to secure by Letters Patent, is:—

1. A sewing machine including in combination a needle bar, a plurality of needles carried thereby, an arm secured to the needle

bar and having thread guides for the needle threads, a support, a series of tension discs mounted on said support one for each needle thread, said discs being located one above another, a stationary arm located between the tension discs and the arm on the needle bar and having a series of thread guides for the needle threads, means for supporting said stationary arm so that the same may be raised and lowered and means for supporting said arm so that the same may be shifted toward or from the needle bar.

2. A sewing machine including in combination a needle bar, a plurality of needles carried thereby, an arm secured to the needle bar and having thread guides for the needle threads, a support, a series of tension discs mounted on said support one for each needle thread, said discs being located one above another, a stationary arm located between the tension discs and the arm on the needle bar and having a series of thread guides for the needle threads, means for supporting said stationary arm so that the same may be raised and lowered or shifted toward or from the needle bar, said last-named arm having a laterally projecting portion for the thread guides, said means for supporting said arm including a sleeve in which said arm is mounted for endwise movement and also oscillating movement.

3. A sewing machine including in combination a support, a series of posts mounted on said support one above the other, each post having a shoulder thereon spaced from said support, a pair of tension discs on each post normally resting against said shoulder, tension means for pressing the discs against the shoulder, thread guides for guiding an independent thread to each pair of tension discs, a plate having an opening therethrough adapted to receive said posts and slidable on the posts between the support and the shoulder, an arm on said plate for each pair of tension discs, said arm being located between the tension discs and having a wedge-shaped upper edge portion adapted to pass between the discs and separate the same when the plate is raised, and means under the control of the operator for raising said plate.

4. A sewing machine including in combination a support, a series of posts mounted on said support one above the other, each post having a shoulder thereon spaced from said support, a pair of tension discs on each post normally resting against said shoulder, tension means for pressing the discs against the shoulder, thread guides for guiding an independent thread to each pair of tension discs, a plate having an opening therethrough adapted to receive said posts and slidable on the posts between the support and the shoulder, an arm on said plate for each pair of tension discs, said arm being located between the tension discs and having a wedge-shaped

upper edge portion adapted to pass between the discs and separate the same when the plate is raised, and means under the control of the operator for raising said plate, said means for raising the tension releasing plate including devices for raising the presser foot of the sewing machine, said means for raising the tension releasing plate being adjustable so as to vary the extent of movement imparted to said tension releasing plate.

5. A sewing machine including in combination an overhanging arm, a bracket carried by said arm, a support extending in a vertical direction attached to said bracket, a series of posts mounted on said support one above another, each post having a shoulder adjacent the support, a pair of tension discs on each post, a spring for pressing said tension discs against the shoulder, means 15 for varying the tension on said discs, said support carrying thread guides for guiding thread between the tension discs, said thread guides being located in a line beneath the posts with which they are associated, a plate 20 carried on said support for vertical movement, said plate having an arm associated with each pair of discs located beneath the discs and provided with a wedge-shaped portion at its upper edge adapted to pass between the discs when the plate is raised for separating the discs, and means for raising and lowering said tension releasing plate.

6. A sewing machine including in combination an overhanging arm, a bracket carried by said arm, a support extending in a vertical direction attached to said bracket, a series of posts mounted on said support one above another, each post having a shoulder adjacent the support, a pair of tension discs 25 on each post, a spring for pressing said tension discs against the shoulder, means for varying the tension on said discs, said support carrying thread guides for guiding thread between the tension discs, said thread guides being located in a line beneath the posts with which they are associated, a plate carried on said support for vertical movement, said plate having an arm associated with each pair of discs located beneath the 30 discs and provided with a wedge-shaped portion at its upper edge adapted to pass between the discs when the plate is raised for separating the discs, and means for raising and lowering said tension releasing plate, said last-named means including devices for raising the presser foot of the machine when the tensions are released, and adjustable devices for raising and lowering the tension releasing plate so that the extent of movement imparted thereto may be varied.

7. A sewing machine including in combination a plurality of tensions arranged one above another, each of said tensions having a 35 pair of tension discs, a support upon which

said tensions are mounted, a reciprocable member located between said tension discs and said support, thread guides located in said support adapted to lead the threads to and away from said tensions, and arms carried by said member and disposed so as to engage and separate said tension discs when said member is moved in one direction.

In testimony whereof, I affix my signature.

RALPH S. KELSO.

In testimony whereof, I affix my signature.

JAMES R. MOFFATT.
